US0D1025187S

(12) **United States Design Patent** (10) **Patent No.:** **US D1,025,187 S**
(45) **Date of Patent:** **** Apr. 30, 2024**

(54) **FILTER**

(71) Applicant: **SHENZHEN NEEWER TECHNOLOGY CO. LTD**, Shenzhen (CN)

(72) Inventors: **Jun Wang**, Shenzhen (CN); **Yan Ke**, Shenzhen (CN)

(73) Assignee: **SHENZHEN NEEWER TECHNOLOGY CO. LTD**, Shenzhen (CN)

(**) Term: **15 Years**

(21) Appl. No.: **29/861,564**

(22) Filed: **Nov. 30, 2022**

(30) **Foreign Application Priority Data**

Oct. 31, 2022 (CN) 202222892104.0

(51) **LOC (14) Cl.** **16-05**

(52) **U.S. Cl.**

USPC **D16/237**

(58) **Field of Classification Search**

USPC D16/100–101, 130, 134, 200, 202, 204, D16/208–209, 216–220, 230, 237, 242, D16/245, 248, 250, 300, 301, 304, 313, D16/334; D23/209–210, 365; D7/400; D24/162

(57) **CLAIM**

The ornamental design for a filter, as shown and described.

DESCRIPTION

FIG. 1 is a top perspective view of a filter showing our new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a top perspective view thereof, shown in a disassembled state.

The dash-dash broken lines in the drawings depict the portions of the filter which form no part of the claimed design.

1 Claim, 9 Drawing Sheets
